(57) **CLAIM**

The ornamental design for an arcade machine, as shown and described.

DESCRIPTION

FIG. 1 is an isometric view of an arcade machine.

FIG. 2 is an obverse isometric view of the arcade machine of FIG. 1.

FIG. 3 is a top plan view of the arcade machine of FIG. 1.

FIG. 4 is a front elevation view of the arcade machine of FIG. 1.

FIG. 5 is a rear elevation view of the arcade machine of FIG. 1.

FIG. 6 is a left side elevation view of the arcade machine of FIG. 1; and,

FIG. 7 is a right side elevation view of the arcade machine of FIG. 1.

Portions of FIGS. 1 through 7 are shown in evenly spaced broken lines illustrating portions of the arcade machine that form no part of the claimed design.

1 Claim, 7 Drawing Sheets
